CLAIM

The ornamental design for a telephone set, as shown and described.

DESCRIPTION

FIG. 1 is a front, top and right side perspective view of a telephone set showing my new design in cradled position;

FIG. 2 is a rear elevational view thereof;

FIG. 3 is a bottom plan view thereof;

FIG. 4 is a left side elevational view thereof; and

FIG. 5 is a top plan view of the stand and a bottom plan

view of the handset shown in bracketed relationship.

The broken line showing of circular center portions of pushbutton keys in FIGS. 1 and 5 is for illustrative purposes only and forms no part of the claimed design.
